(57) **CLAIM**

The ornamental design for an end piece for a cargo securement cable, as shown and described.

DESCRIPTION

FIG. 1 is a front-top-left perspective view of an end piece for a cargo securement cable of the present disclosure;

FIG. 2 is a top planar view of the end piece for a cargo securement cable of the present disclosure;

FIG. 3 is a bottom planar view of the end piece for a cargo securement cable of the present disclosure;

FIG. 4 is a front planar view of the end piece for a cargo securement cable of the present disclosure (the rear planar view is a mirror image); and,

FIG. 5 is a left side planar view of the end piece for a cargo securement cable of the present disclosure (the right side planar view is a mirror image).

The broken lines in the drawings depict environmental subject matter that forms no part of the claimed design.
